Primary Examiner — George J Ulsh*Assistant Examiner* — Kathryn Elizabeth Zieno(74) *Attorney, Agent, or Firm* — Husch Blackwell LLP(57) **CLAIM**

The ornamental design for a drain grate as shown.

DESCRIPTION

FIG. 1 is a top perspective view of a drain grate.

FIG. 2 is a bottom perspective view of the drain grate of FIG. 1.

FIG. 3 is a front view of the drain grate of FIG. 1.

FIG. 4 is a rear view of the drain grate of FIG. 1.

FIG. 5 is a left-side view of the drain grate of FIG. 1.

FIG. 6 is a right-side view of the drain grate of FIG. 1.

FIG. 7 is a top view of the drain grate of FIG. 1; and,

FIG. 8 is a bottom view of the drain grate of FIG. 1.

The evenly spaced broken lines in the drawings show portions of the drain grate, which form no part of the claimed design.
